(57) **CLAIM**

The ornamental design for sonic bath scrubber, as shown and described.

DESCRIPTION

FIG. 1 is a top, rear, left side perspective view of the present invention;

FIG. 2 is a front elevation view of the present invention;

FIG. 3 is a rear elevation view of the present invention;

FIG. 4 is a right side elevation view of the present invention;

FIG. 5 is a left side elevation view of the present invention;

FIG. 6 is a top, plane view of the present invention; and,

FIG. 7 is a bottom plane view of the present invention.

The broken line structure shown in FIGS. 1 and 2 forms no part of the claimed design.
